UNITED STATES PATENT OFFICE

149,912

DESIGN FOR A LAWN SPRINKLER

Jacob W. Shook, Bellefonte, Pa., assignor to The
Titan Metal Manufacturing Company, Belle-
fonte, Pa., a corporation of Pennsylvania

Application July 11, 1946, Serial No. 131,479

Term of patent 14 years

(Cl. D91—1)

To all whom it may concern:

Be it known that I, Jacob W. Shook, a citizen of the United States, residing at Bellefonte, county of Center and State of Pennsylvania, have invented a new, original, and ornamental Design for a Lawn Sprinkler, of which the following is a specification, reference being had to the accompanying drawings, forming part thereof, and in which drawings:

Figure 1 is a side elevational view of a lawn sprinkler embodying my new design.

Figure 2 is an end elevation; and

Figure 3 is a top plan view thereof.

I claim:

The ornamental design for a lawn sprinkler, as shown.

JACOB W. SHOOK.
